UNITED STATES PATENT OFFICE.

AUGUSTUS L. C. MARSH, OF PLAINFIELD, NEW JERSEY.

ADJUSTABLE PROTECTIVE FRAME.

SPECIFICATION forming part of Letters Patent No. 758,372, dated April 26, 1904.

Application filed July 24, 1903. Serial No. 166,808. (No model.)

To all whom it may concern:

Be it known that I, AUGUSTUS L. C. MARSH, a citizen of the United States, and a resident of Plainfield, in the county of Union and State 5 of New Jersey, have invented certain new and useful Improvements in Adjustable Protective Frames, of which the following is a specification.

This invention relates particularly to adjustable protective frames; and one of its main objects is to provide a protective frame in which the size of the opening may be adjusted or varied within wide limits for the purpose of permitting said frame to be applied to the 15 part to be operated upon and such operation confined to the area inclosed by the opening in the frame.

Specifically, the principal object of the protective frame illustrated in this case is to confine the operation of cleaning or buffing a given article or surface to the area bounded by the inner edges of the frame—that is to say, to confine such operation to the area of said opening.

An important application of the device constituting the subject-matter of this invention is its use as a protective device or guard for preventing the marring of any portion of the surface outside the area bounded by the inner 25 edges of the frame—as, for example, in cleaning escutcheons and other articles which may require to be polished from time to time. In cleaning such articles it is well known that the pomade or other polishing substance is frequently rubbed on the woodwork as well as on the metal, and the wood surrounding the escutcheon or other part is frequently badly marred or stained, particularly when the cleaning substance contains gritty particles, oils, 35 &c., as is usually the case. A protective device of this type is especially adapted for protecting such an article during the cleaning thereof, as the sides of the frame may be made of wide but thin sheet material and lie in close 40 contact with the surrounding surface or wood-work, while forming a sufficiently wide protective frame to prevent any of the cleaning or polishing substance from being rubbed off onto the woodwork or other surface outside 45 50 said frame.

In the drawings accompanying this specification and forming part of the present application, Figure 1 is a plan of an adjustable frame embodying my invention and illustrates in full and dotted lines, respectively, two positions of the parts for inclosing articles or surfaces of different sizes or areas. Fig. 2 is a similar view illustrating a modification of the invention. Fig. 3 is an enlarged sectional detail of a portion of the modification shown 55 in Fig. 2.

Similar characters designate like parts in all the figures of the drawings.

My invention is embodied in any protective device in which an adjustable frame is formed 65 by a plurality of frame-pieces capable of adjustment for varying the size of the opening in the frame; but it will preferably comprise a pair of complementary frame-pieces, which may be relatively wide and thin and which 70 will be adjustable to vary the size of the opening included by them. These two complementary frame-pieces are also preferably rectangular, and when so made a square or oblong opening of any dimensions within the limits of 75 the frame-pieces may be formed to correspond to the requirements of the work to be done.

Whatever the particular construction may be in which the invention is embodied the elements of the frame will preferably be so constructed as to be easily connectible to form a stiff frame, and my invention embodies an adjustable frame in which the frame-pieces are in frictional sliding engagement with each other for the purpose of varying the area of 85 the opening and correspondingly varying the area of the main portion of the frame. In both forms of the device shown in the drawings the frame consists of elements which are interlocked in such a manner that they will 90 preferably maintain themselves in the position in which they may be set. Usually the frame will consist of two complementary frame-pieces, preferably rectangular, and these parts may not only be complementary, 95 but may also be interchangeable, and hence both of these parts are designated herein by 2. Each of the members 2 will usually be constructed of sheet material, preferably sheet metal, having one relatively long arm and a 100

shorter arm, preferably at a right angle thereto, of considerably greater width than the long arm. Each of these short arms 3 may be so formed as to provide a means of connection 5 with and adjustment relative to the long arm of the other or complementary frame-piece, and when it is made of sheet material the necessary means of connection and adjustment may be provided by slitting the short arm of 10 the frame-piece and expanding the material depthwise, substantially in the manner of expanded metal lathing and similar articles. In order to hold the coacting arm of the complementary frame-piece firmly, each of these 15 arms which is so cut and expanded will preferably be slotted along two substantially parallel lines, such as 4 and 5, and that part of the arm 3 which is between said slits and is designated by 6 will be expanded relatively 20 to the remainder of such arm to form a guideway through which the coacting end of the complementary frame-piece may be passed and in which such coacting element may work. The expanded portion 6 of each arm 3 and the 25 portions outside of the lines 4 and 5 will exert sufficient tension on the arms 2, which are passed through the guideways formed in the arms 3 and are interlocked therewith to hold the arms 2 firmly in position, while permitting 30 them to slide in frictional engagement with the various portions of the arms 3 whenever it is desired to change the adjustment and vary the size of the opening in the frame.

In order to facilitate the adjustment of the 35 frame to a new position in which the opening in the frame shall be perfectly regular, particularly when the frame is made up of complementary rectangular pieces and the opening must be either a square or an oblong, I 40 prefer to provide at the inner edges of the frame-pieces scales, such as 7 and 8, having similar graduations, by means of which it may be instantly determined whether the four corners of the frame-opening are true right angles. 45

Although the adjustable frame shown in Fig. 1 is made up of parts which are capable of maintaining any desired position in which these parts may be set, yet it may be desirable for some purposes to provide additional 50 means for positively securing the parts together and preventing change in the adjustment thereof. For this reason I have shown in Figs. 2 and 3 a modification of the invention in which the frame-pieces 2 2 are exactly 55 the same as in Fig. 1, but are positively secured in their adjusted position by suitable holding means. The holding means may be of any suitable construction and may be employed at one point only in the frame or at 60 diagonal points, as may be desired. The device shown is illustrated, however, as clamping the parts together at one corner only of the frame and is in the form of a slide 9, 65 mounted on one of the long arms 2 outside

the short arm 3 of the complementary frame-piece and having an extension 10 of sufficient length to project over the struck-up or expanded portion 6 of the short arm 3 of the complementary member of the frame. When 70 in its clamping position, the end of the slide proper is preferably in contact with the outer edge of the arm 3 of the complementary member of the frame and is secured to the long arm 2 of its own member by means of a clamp-screw 11. A similar clamping-screw 12 in the extended portion 10 of the slide serves to engage the expanded portion 6 of the frame-piece 3 of the complementary member and hold both members of the frame firmly together. This holding device, it will be seen, admits of the clamping of the two members of the frame together with the slide at any point in the length of the arm 2 of its own member and with a clamp-screw 12 engaging the expanded portion 6 of the complementary member at any point in the length thereof without presenting any unnecessary openings through which the polish or other substance may be brought in contact with a portion of the surface outside of that to be operated upon or cleaned. 85

What I claim is—

1. A protective device of the class specified, comprising an adjustable frame made up of 95 frame-pieces in frictional sliding engagement with each other for varying the size of the opening in the frame.

2. A protective device of the class specified, comprising an adjustable frame made up of 100 complementary frame-pieces one of which is adjustable in two directions relatively to the other for varying the size of the opening in the frame.

3. An adjustable frame consisting of frame-pieces in frictional sliding engagement with each other in two directions transverse to each other for varying the size of the opening in the frame. 105

4. An adjustable frame consisting of interlocking strips of sheet material in sliding engagement with each other for varying the size of the opening in the frame. 110

5. An adjustable frame consisting of strips of sheet material slotted and interlocked in 115 sliding engagement with each other for varying the size of the opening in the frame.

6. An adjustable frame consisting of a pair of interlocking angular frame-pieces of sheet material in sliding engagement with each other 120 for varying the size of the opening in the frame.

7. An adjustable frame consisting of a pair of interchangeable rectangular frame-pieces of sheet material slidingly interlocked for 125 varying the size of the opening in the frame one arm of each rectangular frame-piece being slotted along substantially parallel lines and expanded depthwise to form a guideway for the other arm of the other frame-piece. 130

8. An adjustable frame consisting of frame-pieces in frictional sliding engagement with each other for varying the size of the opening in the frame, and means for holding said frame-pieces in any adjusted position.

9. An adjustable frame consisting of a pair of interchangeable rectangular frame-pieces of sheet material slidingly interlocked for varying the size of the opening in the frame, and sliding holding means on said frame for

locking the frame-pieces in any adjusted position.

Signed at New York, in the county of New York and State of New York, this 21st day of July, A. D. 1903.
